UNITED STATES PATENT OFFICE.

VINCENZO MANCINI, OF SCHENECTADY, NEW YORK.

DETACHABLE HORSESHOE.

1,037,947.

Specification of Letters Patent. Patented Sept. 10, 1912.

Application filed January 9, 1912. Serial No. 670,185.

To all whom it may concern:

Be it known that I, VINCENZO MANCINI, a subject of the King of Italy, residing at Schenectady, county of Schenectady, and 5 State of New York, have invented certain new and useful Improvements in Detachable Horseshoes, of which the following is a specification.

The invention relates to such improvements and consists of the novel construction 10 and combination of parts hereinafter described and subsequently claimed.

Reference may be had to the accompanying drawings, and the reference characters 15 marked thereon, which form a part of this specification. Similar characters refer to similar parts in the several figures therein.

Figure 1 of the drawings is a view in side elevation showing my improved detachable 20 horseshoe applied to a horse's hoof. Fig. 2 is a top plan view of the shoe with the clamping-mechanism closed. Fig. 3 is a similar view with the clamping-mechanism open. Fig. 4 is a plan view of one of the 25 bail-members detached. Fig. 5 is a view in side elevation of the same. Fig. 6 is a vertical cross-section taken on the broken line 6—6 in Fig. 1, through one of the calks. Fig. 7 is a plan view of the blank adapted 30 to be bent up to form the body of the shoe. Fig. 8 is a side view of the stop-block and the pivot-pin upon which the same is eccentrically mounted. Fig. 9 is a plan view of the tread-plate detached. Fig. 10 is a 35 bottom plan view of the toe-portion of the shoe, showing a preferred form of toe-calk.

Certain objects of the invention are to facilitate the attachment as well as the removal of the shoe; to securely hold the shoe 40 in place upon the hoof; to prevent injurious pressure upon the hoof by the heel-portion of the attaching mechanism; and to securely yet removably attach a calk to the body of the shoe.

45 Other objects will appear in connection with the following description.

Referring to the drawings wherein the invention is shown in preferred form, 1, represents the body of the shoe having a 50 rigid toe-clip, 2, and smaller side-clips or

lugs, 3, said clips being adapted to overhang the front portion of the hoof in use.

A pair of bail-members, 4, are pivotally mounted upon the heel-portion of the shoe by means of vertical pivots, 5, and are 55 adapted to embrace and be clamped upon the hoof to secure the shoe thereto. The bail-members, 4, are preferably made of resilient sheet-metal, and each has a flat horizontal heel-portion, 4^a, adapted to rest 60 flatly upon the heel of the shoe; and each bail-member is bent to curved form and given a slightly more than half twist whereby it is adapted to conform substantially to the surface of the hoof when the bail is 65 clamped upon the hoof in an oblique position, as shown in Fig. 1. The front end of each bail-member, 4, is thus inclined to correspond substantially with the inclination of the toe-clip, 2, and the toe-clip is 70 provided on its outer side with a groove, 6, adapted to receive the front ends of the bail-members, and to prevent them from bearing directly upon and injuring the hoof. The front end of each bail-member is offset or 75 bent to form an attaching lug, 7, apertured to receive the screw-bolt, 8, one of said apertures being screw-threaded to engage the screw-threads on said bolt.

The shoe is applied to the hoof with the 80 bail-members, 4, separated, as shown in Fig. 3, the hoof being inserted beneath the overhanging clips, 2 and 3, and the bail-members are then brought together outside of the toe-clip, 2, with their ends seated in the groove, 85 6, in the toe-clip, after which the bail-members are drawn together by means of the bolt, 8, until the hoof is securely clamped, so that the shoe will be held 90 securely thereupon.

I have shown a stop-block, 9, mounted upon the heel-portion of the shoe, and the heel-portion of each of the bail-members formed with a lug, 10, adapted to engage said stop-block to limit the rotative movement of the bail-member upon its pivot 5. The stop-block, 9, is so located in a shoe adapted for a particular horse's hoof that it will be engaged by the lugs, 10, and prevent further pivotal movement of the bail-mem- 100

bers upon their pivots, 5, before the upturned heel-portions of the bail-members can exert injurious pressure upon the tender heel-portion of the hoof. By properly 5 locating the stop-surface of the stop-block, 9, relatively to the lugs, 10, I am able to adapt the size of the heel-portion of the attaching-mechanism nicely to the size of the heel-portion of the hoof, the resiliency of 10 the bail-members permitting their front ends to be drawn together sufficiently to securely clamp the hoof as above explained. The stop-block, 9, may be mounted upon the heel-portion of the shoe in any known manner, but is preferably removably mounted 15 thereupon, whereby blocks of different sizes can be employed upon the same shoe. In the preferred form of my invention I have shown the stop-block mounted eccentrically 20 upon a pin, 11, adapted to engage a similarly threaded aperture in the heel of the shoe, the block being of polygonal form. The block can be thus rotatively adjusted to bring one or another of its sides into the 25 path of the lugs, 10, on the bail-members, such adjustment being sufficient to provide for ordinary use, while the block can be entirely removed and replaced by one of different size if desired.

30 I have shown the shoe provided with removable calks, 12, each having a screw-threaded shank, 13, adapted to engage a similarly threaded aperture in the body of the shoe, and each having a malleable flange, 35 14, adapted to be bent over the edge of the body of the shoe after the calk has been screwed to its seat to prevent the calk from working lose by a reverse or unscrewing movement. To facilitate thus locking the 40 calk upon the shoe, the edge of the shoe may be chamfered or cut away opposite the calk, as shown in Fig. 6.

The body of the shoe is preferably made 45 of malleable metal, as rolled iron or steel, and is stamped or cut from the sheet of metal in the form shown in Fig. 7, after which the blank so formed is bent up to the shape shown in Figs. 1, 2 and 3. The body of the shoe may, however, be formed in 50 any known manner and of any desired material suitable for horeshoes.

When the body of the shoe is made of a comparatively soft metal, I apply to the underside thereof a tread-plate, 15, of hard 55 metal, as sheet-steel, to protect and relieve the soft metal body of the shoe from wear. This tread-plate is apertured to receive the screw-threaded shanks, 13, of the calks, 12, which serve to hold the tread-plate upon 60 the body of the shoe.

The tread-plate as well as the calks can be renewed from time to time. To remove the calks it is necessary merely to bend back the upturned edge of the flange, 14, where-

upon the calk can be unscrewed and removed. 65

The head of the clamping-bolt, 8, is provided with an aperture, 17, adapted to receive a key, 18, to lock the bolt against rotation after the bail-members have been 70 drawn tightly together.

In Figs. 1 and 10, I have shown a preferred form of toe-calk, 19, the projecting portion of the same being of skeleton form and having cutting edges, 20, extending 75 longitudinally of the shoe, and other cutting edges, 21, extending transversely of the shoe at right angles to the cutting edges 20. The cutting edges, 20, serve to prevent side slip, while the cutting edges, 21, afford 80 a good purchase for the toe upon the road-bed. This toe-calk may be secured upon the body of the shoe by any suitable connecting mechanism, such as bolts or rivets, 22, said connections passing through 85 the tread-plate, 15, if the tread-plate is used.

The skeleton form of calk just described is preferably secured to the body of the shoe by means of a plurality of connections whereby rotative displacement of the calk is 90 rendered impossible, thus insuring the retention of its cutting edges in the proper lines.

What I claim as new and desire to secure by Letters Patent is—

95

1. A detachable horseshoe comprising in combination the shoe-body; a pair of bail-members formed of resilient sheet-metal, each having a heel-portion pivotally mounted upon the heel of the shoe-body upon a vertical axis, and having a lug on said heel-portion, said bail-members being adapted to embrace the hoof to which the shoe is attached; a stop-block in the path of said lugs on the heel-portions of the bail-members 105 whereby their rotative movement is limited; and means for securing together the front ends of said bail-members.

2. A detachable horseshoe comprising in combination the shoe-body; a pair of bail-members formed of resilient sheet-metal, each having a heel-portion pivotally mounted upon the heel of the shoe-body upon a vertical axis, and having a lug on said heel-portion, said bail-members being adapted to 110 embrace the hoof to which the shoe is attached; a polygonal stop-block; a pin adjustably mounted in the heel-portion of the shoe-body, upon which pin said stop-block is eccentrically mounted in the path of said 115 lugs upon the bail-members whereby their rotative movement is limited; and means for securing together the front ends of said bail-members.

120

3. In a detachable horseshoe, and in combination, a shoe-body having a toe-clip; a pair of bail-members formed of resilient sheet-metal, each having a heel-portion piv-

125

totally mounted upon the heel of the shoe-body upon a vertical axis, and having a lug on said heel-portion, and each bent to curved form and having a twist whereby its front end is inclined to conform to the hoof to which the shoe is attached; means for drawing together the front ends of said bail-members; and a stop-block in the path of

said lugs on the bail-members whereby their rotative movement is limited.

10

In testimony whereof, I have hereunto set my hand this 2nd day of January 1912.

VINCENZO MANCINI.
